UNITED STATES PATENT OFFICE.

WILLIAM FORESTER DOBBS, OF WINDHAM, OHIO.

WIRE-FENCE MACHINE.

SPECIFICATION forming part of Letters Patent No. 569,487, dated October 13, 1896.

Application filed December 3, 1895. Serial No. 570,911. (No model.)

To all whom it may concern:

Be it known that I, WILLIAM FORESTER DOBBS, of Windham, in the county of Portage and State of Ohio, have invented certain new and useful Improvements in Wire-Fence Machines; and I do hereby declare the following to be a full, clear, and exact description of the invention, such as will enable others skilled in the art to which it appertains to make and use the same.

This invention contemplates certain new and useful improvements in wire-fence machines, and has for its objects to provide a light, portable device which can be easily and quickly moved along a line of stretched fence-wire, and also simple and highly-efficient means for twisting vertical strands of wire across the horizontally-stretched wires.

The invention will be hereinafter fully set forth, and particularly pointed out in the claims.

In the accompanying drawings, Figure 1 is a front elevation. Fig. 2 is an end view. Fig. 3 is an enlarged perspective view of the twisting-head. Fig. 4 is a top plan view of the carriage. Fig. 5 is a longitudinal sectional view thereof. Fig. 6 is a transverse sectional view on line 6 6, Fig. 5.

Referring to the drawings, A designates the portable frame; a, a truck; a', carrying-wheels therefor, and a² a³ uprights secured at their lower ends to one end of truck a, the upright a³ being parallel with and set at right angles to the upright a². Between the upper ends of these uprights is secured an arm a⁴, which overhangs the truck. The upright a³ is removably held at its ends by bolts a⁵. These uprights are located, in practice, on opposite sides of the horizontal fence-wires w. To the upright a³ is secured a series of angular arms b, having opposite slotted lugs b' to grasp and accommodate the wires w. To permit of the adjustment of these arms on upright a³, the latter is provided with numerous holes b², through the desired ones of which the holding-screws or bolts b³ are passed.

C designates an endless sprocket-chain which engages upper and lower sprocket-wheels d d', whose journals extend from arm a⁴ and truck a, respectively. One portion of this chain travels at right angles to and parallel with the front face of upright a³.

D is an upright rod pivotally supported at its ends by truck a and arm a⁴. On this rod are adjustable gripping-arms d², having slots d³ to allow said arms to engage the wires w. To an angular arm d⁴, extending from the upper end of this rod, is connected one end of a coil-spring d⁵, the other end thereof being secured to the inner end of arm a⁴. This spring serves to hold the gripping-arms against the wire w or away therefrom when the rod is turned, so as to allow said arms to be thrown into a position opposite to that in which they are shown in the drawings. A handle-bar d⁶ is secured to the rod D. A bar d⁷ parallel with rod D is secured at its upper end to arm a⁴ and at its lower end to the truck. The gripping-arms when in engagement with wires w bear against this bar, thereby preventing said wires from being disengaged from said arms while the twisting is being performed.

E is the carriage, which is vertically adjustable on upright a³. It comprises a frame e, having a groove e' to accommodate said upright. On a journal e² of this frame is mounted a sprocket-wheel e³, which meshes with one leg of the chain C, which is held in close engagement with said wheel by two lazy-wheels e⁴, journaled in the ends of two arms e⁵. On one side of this sprocket-wheel e³ is formed a ratchet-wheel e⁶, with which engages a spring-pressed pawl e⁷, carried by an operating-arm F, mounted at one end on journal e². A hand-lever e⁸ on this arm is connected by a rod e⁹ to the pawl e⁷. By operating this arm the carriage can be raised and lowered. Extending longitudinally through frame E is a shaft f of a twister-head f', which is on the outer end of said shaft. On the latter, within the frame, is a bevel gear-wheel f², with which engages a similar wheel f³ on a short operating-shaft f⁴, extending through a tubular extension f⁵ of one side of frame E, an operating-handle f⁶ being attached to said extended end. From extension f⁵ projects a lug g, which fits in one of the links of the sprocket-chain, said link being securely held by a cap-plate g'. By means of this connection the carriage is raised or lowered by the operation of said chain. Extending longitudinally on each side of the shaft f is a slot g², each of which slots diverges from about its center toward

each end. In this way I avoid straining the wires *w* by the twisting operation. The outer ends of these slots are in close relation to each other and near the center of the twisting-head. Adjacent to these slots at the ends and center are placed jaws *g*³, which serve to direct the wires *w* into said slots. The spool *G* of wire is mounted between lateral arms *g*⁴, extending from shaft *f*. The wire is passed 10 from this spool through a central opening in the twisting-head.

In practice, the frame is first properly positioned, one of its uprights having been removed and again secured in position on the 15 side of the fence opposite the other upright. By operating the arm *F* and the wheel *e*³ the carriage, because of the engagement between lug *g* and chain *C*, can be moved to the top of the frame, so that the topmost wire *w* will 20 be engaged by one of the slotted sides of the twisting-shaft. The wires *w* are grasped by the slotted arms *b*, and also the gripping-arms *d*² of rod *D*. Some of the wire off the spool is preferably twisted along part of the topmost wire, and then by turning the handle *f*⁶ 25 the shaft *f*⁴ is rotated, causing wire from the spool to be twisted around one of the wires *w*. This being accomplished, the carriage is lowered to the next wire *w* and the above operation is repeated to and including the bottom wire. Around this wire some of the 30 spool-wire is twisted, the same as at the top, and then the twisting around each wire *w* is repeated as the carriage is moved upward. 35 The purpose of the vertical stay-wires and the winding of additional wire around the topmost and bottom wires *w* is to prevent the spreading of the fence-wire, so that animals cannot force their heads through the 40 fence.

I claim as my invention—

1. A wire-fence machine, comprising a frame having uprights, sprocket-wheels on said frame, a chain engaging said sprocket-wheels, a carriage adjustable on said frame, a lug projecting from said carriage to which said chain is connected, a wheel on said carriage engaging said chain, means for moving said wheel, and a twister mounted in said 45 carriage, as set forth.

2. A wire-fence machine comprising a frame having uprights, sprocket-wheels on said frame, a chain engaging said sprocket-wheels, a carriage adjustable on said frame, a lug projecting from said carriage to which 55 said chain is connected, a wheel on said carriage engaging said chain, a ratchet-wheel, an operating-handle carrying a pawl engaging said ratchet-wheel, and a twister mounted 60 ed in said carriage, substantially as set forth.

3. A wire-fence machine, comprising a frame having uprights, sprocket-wheels on said frame, a chain engaging said sprocket-wheels, a carriage adjustable on said frame,

a lug projecting from said carriage to which 65 said chain is connected, a wheel on said carriage engaging said chain, means for moving said wheel, a twister having a shaft fitted in said carriage, an operating-shaft, and bevel gear-wheels on said shafts, substantially as 70 set forth.

4. The combination with the frame, the sprocket-wheels and the chain engaging said wheels, of the carriage adjustable on said frame and to which said chain is connected, 75 the wheel on said carriage engaging said sprocket-chain, the operating-handle, the twister having a shaft mounted in said carriage, said shaft having tapered slots in its sides, the twister-head on the outer end of 80 said shaft, and the operating-shaft engaging said twister-shaft, substantially as set forth.

5. The combination with the wheeled truck, of the uprights removably secured thereto, the arm between the upper ends of said uprights, the sprocket-chain and wheels therefor, the carriage vertically adjustable on said uprights, the operating sprocket-wheel mounted on said carriage and engaging said chain, the arms having lazy-wheels holding 90 said chain against said operating-wheel, the operating-handle for moving said latter wheel, the twister having a shaft in said carriage, and means for operating the same, as set forth.

6. A fence-machine having an upright 95 frame and a vertically-adjustable carriage, a twister having a shaft provided with longitudinal slots in its sides, said slots tapering from their centers to the ends, a spool-holder formed on said shaft, a twister-head on one 100 end of said shaft and guiding-jaws on the opposite end thereof, an operating-shaft, a bevel gear-wheel mounted on each of said latter shafts and meshing with each other, and an operating-handle for said operating-shaft, 105 substantially as set forth.

7. The combination with the frame formed of two upright parallel bars, the vertically-adjustable carriage, and the twister, of the series of arms secured to one of said bars and 110 having slotted ends to engage the fence-wires, and the series of arms secured to the other one of said bars and having oppositely-slotted lugs, as and for the purposes set forth.

8. The combination with the upright frame, 115 the vertically-adjustable carriage, and the twister, of the pivoted rod, the gripping-arms extending therefrom having slotted ends, the spring acting on said rod, and the bar parallel with said rod, substantially as set forth. 120

In testimony whereof I have signed this specification in the presence of two subscribing witnesses.

WM. FORESTER DOBBS.
